[57] CLAIM

The ornamental design of a telephone handset, as shown and described.

DESCRIPTION

FIG. 1 is a bottom, rear and left side perspective view of a telephone handset showing our new design;

FIG. 2 is a top, front and right side perspective view thereof;

FIG. 3 is a rear elevation thereof;

FIG. 4 is a front elevation thereof;

FIG. 5 is a right side elevation thereof;

FIG. 6 is a left side elevation thereof;

FIG. 7 is a bottom plan view thereof; and,

FIG. 8 is a top plan view thereof.

The broken line showings throughout the views are for illustrative purposes only and form no part of the claimed design.

FIG. 1

FIG. 2
